ABSTRACT OF THE DISCLOSURE

The novel flowing mercury cathode electrolytic cell has an improved bottom with alternate bare and insulated lengthwise segments, anodes above the bare segments, and adjustable support means for the anodes extending through insulating sleeves in the insulated segments of the cell bottom to adjustment means below the cell bottom. The top and sides of the cell are advantageously constructed of light weight materials since they do not have to support the anodes and anode adjustment means.

This invention relates to the suspension of anodes in electrolytic cells and is more particularly concerned with improved means for supporting the anodes from below the cell and avoiding the heavy cover and superstructure usually necessary.

Electrolytic cells are employed for the decomposition of solutions of alkali metal compounds using a mercury cathode which flows along the bottom of the cell and a plurality of anodes usually composed of a plate-like element supported from above by a stem, or stems. These plate-like elements have their bottom surfaces parallel to the surface of the mercury and spaced a short distance above it. An aqueous solution of alkali metal compound, commonly a halide, for example, sodium chloride flows through the cell and immerses the anodes and parts of the stems. A thin layer of the solution thus occupies the space between the upper surface of the mercury and the bottom surface of the anode. D.C. current passes through the anodes, through the thin layer of solution and to the mercury cathode, liberating chlorine gas and forming sodium amalgam.

Extreme care must be taken to prevent any direct contact between the anode and cathode which would form a short circuit for the heavy current flowing through the cell. Nevertheless, as the operation of the cell continues, the anodes, when they are of graphite, are consumed upwardly from the bottom face. This increases the space between the bottom surface of the anodes and the mercury until it becomes too great for effective operation. It is, accordingly, necessary to lower such graphite anodes from time to time and it is advantageous to do so while the operation of the cell continues.

Heretofore, the anode stems carrying the anodes have passed through a cell cover and were supported on a superstructure resting on the cover or sides of the cell. Means for adjusting the elevation of the anodes above the mercury surface are usually added to the superstructure. As a result the superstructure and the cover are usually massive. When anodes must be replaced, it is necessary to lift the heavy cover and superstructure and, as cells become ever larger, the cranes to perform this operation become larger.

The structure of the present invention solves these prior

2

art problems in a novel and unexpectedly advantageous manner by supporting the anodes and adjustment means from below the cell. This permits the use of a light weight cell cover and avoids the necessity for a heavy crane when replacing anodes. In addition, suitable means are advantageously provided below the cell for adjustment of the elevation of the anodes above the mercury cathode. The structure of this invention is simple, economical, labor-saving and effective. It is suitable for support on concrete pedestals with no enclosing building.

Generally this invention relates to improved anode support means in combination with an improved cell bottom in a mercury cathode cell for the electrolysis of aqueous solutions, said cell generally comprising an inclined trough having a cell bottom, sides and a cover, inlet and outlet means for said aqueous solution, inlet means for mercury and outlet means for amalgam, chlorine outlet means, anodes supported within said trough and spaced above a mercury cathode flowing over said cell bottom and means for imposing an electric current on said anodes and cathodes. The improved anode support means comprises:

(1) An anode support frame adjustably suspended in spaced relation below said cell bottom and insulated therefrom;

(2) Inverted cups supporting from their lower perimeters a plurality of said anodes in spaced relation to each other and to said cathode;

(3) Electrically conductive anode support rods extending upwardly from said frame through apertures in said cell bottom and terminating below the cover of said trough in the bottom of said inverted cups; and

(4) Insulating sleeves spaced from and surrounding said anode support rods from said cell bottom upwardly to the lower perimeter of said cup; said sleeves closing said apertures in said bottom to the flow of said solution, said mercury and said amalgam.

The improved cell bottom in combination with said improved anode support means comprises bare lengthwise segments of cell bottom alternating with insulated lengthwise segments with said apertures and said sleeves being located in said insulated lengthwise segments.

The invention will be readily understood from the accompanying figures.

Accompanying FIG. 1 shows a cell viewed from the end with the end plate removed. The cell is enclosed by bottom 11, side 12 and top 13. Anodes 14 are indirectly supported on ganged anode support frame 15 which also suitably carries current to the anodes by means of a bus (not shown). Cell bottom 11 is suitably supported, for example, on concrete piers (not shown) at appropriate elevations to provide the desired slope of the cell bottom. The cell bottom is built up of lengthwise segments which

55 are alternately bare and rubber covered. Bare segments 34 are suitably iron channels milled on the upper side to provide a bed for the flow of mercury and amalgam without obstruction. Segments 35 are also suitably iron channels covered by rubber layer 36 and each rubber covered channel is bolted to the adjacent bare channel 34. Sides are formed for the cell by upward extension 12 of rubber covered iron. Threaded frame adjusting rods 16 pass through insulating plastic blocks 17 inset into frame 15 and threaded into nuts inset into the lower side of blocks 17. Rods 16 terminate at their ends in thrust

bearings not seen in FIG. 1 but more particularly shown in FIG. 2. Rods 16 terminate at their lower ends in sprockets 18 engaged by chain 19. Anode support rods 20, anchored on frame 15 by nuts 21 pass upwardly through holes in insulated segments 35 and through sleeves 22 threaded into segments 35 as shown in greater detail in FIG. 3. Rods 20 terminate at their upper ends by threading into the underside of inverted cups 23. Cups 23 are integral with or welded to anode support block 24, suitably shaped as a box. By means of tie rods 25 and end blocks 26, a plurality of anodes are clamped together.

FIG. 2 shows in detail the upper end of frame adjusting rods 16 terminating in a head 30 and engaged in thrust bearing 28 attached to cell bottom 11 by studs 29. This provides support for frame 15 and the anode supporting structures attached thereto.

FIG. 3 shows in detail an anode support rod 20 passing upwardly through cell bottom segment 35. Sleeve 22 is threaded into segment 35 and seals against insulating rubber layer 36. Clearance between rod 20 and sleeve 22 allows the passage of air inside sleeve 22 and cup 23 and out through vent 33 to provide ventilation. Rod 20 terminates at its upper end in threaded engagement with the bottom of cup 23. The perimeter of cup 23 is welded by bead 30 to the top of anode support block 24. Tie rod 25 holds anode 14 tightly in contact with anode support block 24.

FIG. 4 shows one advantageous means for arranging the cathode bus. Cathode current is supplied to bare sections 34 of the cell bottom by buses 37 clamped between the flanges of bare section 34 and rubber covering 36.

FIG. 5 shows a lengthwise section of the lower end of the cell with a suitable arrangement for controlling brine level in the cell, removal of chlorine and amalgam from the cell. Anode 14 is suspended above cell bottom 11 by means of anode support rod 20 passing through sleeve 22 as previously described. A well 38 is provided for the accumulation of amalgam which flows out of the cell via line 39 to a suitable decomposer (not shown). Brine overflows weir 40 which maintains the level of brine under the cups in the cell. Weir 41 closes the gas space above the brine in the cell to hold chlorine gas in the cell above the brine level until it is removed from the cell via line 42 to the chlorine recovery system. A slight reduction of pressure below atmospheric is maintained in the cell to insure against chlorine leakage. The reduced pressure tends to lift the brine level in the cell above that provided by weir 40. Float 43 rides freely on guide 44 in turn supported by vanes 45. This serves to throttle line 42 should the brine rise sufficiently to become entrained in the chlorine gas. Baffle 46 dips in the brine upstream from the float to provide a quiescent area for the float. In addition, weir 47 extends across the cell below the brine level and into amalgam well 38 to separate brine from amalgam. Brine overflowing weir 40 leaves the cell via line 48 for brine treatment and recycle. In cell top 13, vent 49 is advantageously provided downstream from weir 41 to provide atmospheric pressure in the brine overflow section at the outlet end of the cell.

The sleeves 22 are suitably formed of unplasticized polyvinyl chloride but other non-conductor materials are appropriately used including rubber, polymeric trifluorovinyl chloride, polymeric tetrafluoroethylene, ceramics and other materials resistant to the brine to which they are exposed.

The sleeves are tubular in form having an internal diameter sufficient to allow passage of the anode support rod with convenient clearance, suitably $\frac{1}{16}$ to $\frac{1}{4}$ inch. At the lower end, the sleeves have a shoulder and below the shoulder a threaded portion adapted to engage a correspondingly threaded hole in the cell bottom. The length of the sleeves is sufficient to extend above the expected brine level inside the cap, usually about 1 inch above the top of newly installed anodes having the maximum designed thickness.

Anode support rods 20 are suitably formed of highly electrically conductive material, for example, copper, silver, aluminum or alloys thereof, including brass, of sufficient diameter to support the load of clamping pieces and anodes. The rods may be circular or other shape in cross-section and about $\frac{1}{2}$ to 1 inch in diameter. At the lower end, these rods are tightly affixed to anode support frame 15. For example, they may be threaded into a hole in the frame or into a nut welded to frame 15. At the top, the anode support rods are fixedly attached by threaded means or otherwise to anode support cups 23. The anode support rods are advantageously coated with a chlorine resistant coating, for example, silver, polymeric tetrafluoroethylene or polyvinyl chloride to prevent corrosion.

Anode support cups 23 are provided between the anode support rods and the anode support blocks 24. The cups project into the gas space in the cell above the brine level and preferably each has a vent 33 in the top. Pressure less than atmospheric is maintained in chlorine line 42 and in the gas space above the brine in the cell to insure against leakage of chlorine to the atmosphere. Air is drawn into the gas space in the cell through the vent in the top of cup 23. The air flow from below the cell into the annular clearance between rod 20 and sleeve 22 and inside cup 23 serves to remove any corrosive gases which may be contributed from the surface of the brine trapped between the top of sleeve 22 and the bottom of cup 23 or the hole in block 24. The amount of such gas is extremely minor because the brine in this area is relatively stagnant and the exposed surface is very small. For this reason vent 33 may be omitted.

Cups 23 suitably have a length approximating the thickness of graphite anodes, when graphite anodes are used in the cells, so that as the graphite is consumed, the anodes and cups can be lowered to maintain desired anode-cathode distance, the bottom of the inverted cups clearing the top of sleeves 23.

Cups 23 are preferably fabricated of titanium which is most resistant to the brine and gas in the electrolytic cell. Other metals suitable for fabrication of the cup include, for example, silver or silver-coated copper or other materials resistant to the hot brine and gas to which they are exposed, including tantalum, alloys or titanium or tantalum containing up to 15% zirconium, niobium or one of the platinum group metals, i.e., platinum, rhodium, ruthenium, osmium, iridium and palladium.

Anode support blocks 24 are suitably fabricated from channels or from solid blocks. The blocks 24 and end blocks 26 are of any of the same materials as cups 23, preferably titanium. End blocks 26 and blocks 24 are drawn together by tie rods 25 and nuts 27, also preferably of titanium. The blocks engage a portion of anodes 14 and hold them tightly in good electrical contact. This avoids the problems of electrical conductivity, mechanical strength and chemical resistance which have been encountered in the prior art using lead buttons threaded into recesses in the top of graphite anodes for support. The nip or bite of the support blocks and end blocks on the graphite may be whatever is mechanically and electrically optimum. The smaller this nip, the less will be the anode stub loss. The greater this nip, the lower will be the required bolting pressure and the greater electrical contact. For graphite anodes 8 or 9 inches thick a nip of about $\frac{1}{2}$ inch is sufficient but the nip is suitably from $\frac{1}{4}$ inch to 2 inches or more, if necessary.

The invention is described particularly with reference to graphite plates or blocks as anodes but anodes of any material suitable for this service are similarly supported. Titanium anodes, with one or more of the platinum group metals or their oxides coated on the side of the anode facing the cathode, are especially advantageous.

When the anodes are titanium coated with a platinum group metal, alloy or oxide thereof, the anodes are fabricated in any suitable form, for example, a sheet or

expanded mesh, suitably reinforced as necessary. The anode support blocks are suitably fixedly attached thereto, for example, by bolts or welds for improved electrical contact.

Anodes are arranged in any suitable pattern, for example, five wide by 10 long. Other patterns vary according to the dimensions of the anodes and of the cells. The width of any anode is not limited to that of the bare segment of cell bottom opposite which it is juxtaposed but the anode may overhang the insulated segment of cell bottom.

Anode sets are advantageously assembled on a jig to provide the accuracy required to pass through the apertures in the cell bottom and to mate with the anode support frame.

Anode support frame 15 is suitably formed of channel iron or other sufficiently strong structural members. Advantageously, the anode bus is attached at several points to the frame for good current distribution. The frame is welded or bolted together and suitably punched, drilled and tapped to receive anode support rods 20 and threaded suspension rods 16.

Means shown for moving frame 15 with reference to the cell bottom 11 and thereby adjusting the elevation of anodes 14 above the mercury cathode flowing on cell bottom 11 are sprockets 18 and chain 19. Such means are described in an overhead position in U.S. Patent 3,390,070. However, it is to be understood that other equivalent adjustment means are suitable including, for example, cranks, gear boxes, electric, hydraulic or air-operated motors or other suitable means for turning frame adjusting rods 16. It is a necessary proviso that frame 15 is maintained parallel to cell bottom 11 to avoid jamming the rods or twisting the anodes and their supporting structures.

The cell bottom structure is formed of channel irons with flanges down. The narrower channels 35 are suitably 2 to 4 inches wide and are suitably covered with rubber or other insulating material. Sleeves 22 are suitably spaced on top of the rubber covered narrower channels. Rubber covering 36 on the narrower channels stands above the level of the bare steel cathode, thus providing a well-defined course for the mercury flow without any discontinuities.

The wider channels 34 are appropriately, though not necessarily spaced to match the width of anodes 14. These channels 34 are bare iron or steel machined flat and smooth to support the flowing mercury cathode.

The improved cell bottom avoids mercury flow complications since the sleeves present no discontinuity on the cell bottom. Mercury flows smoothly down the wider channels without any possibility of forming a standing wave on the upstream side of the sleeve or exposing bare steel on the downstream side which would cause hydrogen evolution. The improved cell bottom is more rigid per unit weight of steel than a flat sheet bottom and requires less weight of steel understructure for adequate support. For these reasons the steel cost is less per cell. The cell bottoms are advantageously built up in place from relatively light weight components.

A further advantage of the improved cell bottom is that electrical connection to the cathode is suitably provided by means of sheet copper or aluminum cathode bus bolted into the space between the flanges. If desired, the cathode channel flange or the rubber covering or both is provided with a recess to receive the copper. Preferably a greater number of contact points and greater contact area of the cathode bus with the cathode are provided to compensate for the smaller cross-sectional area of the bare wider channels. Using the improved bottom and arranging the anodes to overhang the insulated segments of cell bottom, the cathode current density is substantially higher than the anode current density. This is advantageous electrically and electrochemically because

the lower current density is on the anode where the greatest inherent irreversible power consumption occurs and the higher cathode current density effects an advantageous saving of mercury.

The brine level in the cell is advantageously though not necessarily controlled by features shown particularly in FIG. 5. The liquid brine level in the cell ordinarily depends on gaseous pressure maintained in the cell which is usually accurate and steady so that further controls are unnecessary. Suitable instrumentation on each cell is provided if additional level control is necessary. However, a level-actuated pressure controller is advantageously built into the cell as more particularly shown in FIG. 5.

Weir 47 is provided to separate amalgam from brine.

15 The amalgam collects in well 38 and flows through amalgam outlet 39. Alternatively, the amalgam suitable flows from the well directly into a decomposer below the cell and integral with or separate from the cell. Weir 41 divides the gas space and dips into the brine to hold the 20 chlorine upstream in the cell. Weir 40 in the outlet end of the cell maintains the brine level in the cell generally above the top of the anodes and allows depleted brine to overflow via line 48 to the brine treatment system. Vent 49 maintains atmospheric pressure downstream of 25 weir 41. In addition, a small weep hole is suitably provided in weir 41 above the liquid level to provide ventilation of that section of the cell downstream from weir 41. Weirs 41 and 47 suitably have weep holes at the 30 level of the cell bottom to permit the brine to flow completely from the cell when it is desired to drain the cell.

The tops of sleeves 22 are suitably about $\frac{1}{2}$ to 2 inches, preferably about 1 inch, higher than the top of weir 40. This is sufficient to prevent overflow of brine through the sleeves since atmospheric pressure prevails under cups 35 23 and at the top of sleeves 22.

Reduced pressure in chlorine line 42 and in the cell correspondingly raises the brine level in the cell outside cups 23. To prevent filling the cell with brine even though 40 the pressure differential by some malfunction becomes too large, float 43 is provided below chlorine line 42. Before the brine level rises too high, float 43 throttles line 42 until the pressure differential decreases to normal. The brine level is maintained essentially constant even though the pressure in the chlorine line varies. The brine 45 level under cups 23 is independent of the brine level in the cell and is fixed by the elevation of weir 40. The pressure there and under cups 23 is atmospheric and there is thus no possibility of brine overflowing sleeves 22.

Cell cleaning and anode replacement is accomplished by draining the cell of both mercury and brine, removing the cover with the mobile crane and then removing 55 sets of anodes individually. The cells need be only about 8 to 16 feet above ground level and the mobile crane operates from the ground. It works from both ends of the cells and needs a working reach just over one-half of the cell length, e.g. 25 feet for a 50 foot cell.

60 The structure of the present invention provides a novel cell design which includes the following advantages:

(1) The cell cover and sides are entirely separated from the anodes and anode supports. They are suitably constructed of very light weight materials easily handled 65 by a mobile crane, for example, a "cherrypicker."

(2) The anodes are arranged in sets or gangs. Each set suitably consists of the number of anodes required for the width of the cell. For example, a set of anodes 70 suitably consists of 8 anodes ganged together. This set of anodes is light in weight and is easily handled with a light mobile crane. The novel design has the additional advantage that the anodes are not suspended from a post into the graphite and the anodes have no tendency to break loose and drop into the mercury cathode.

- (3) The structure of this invention also embodies the following features which result in capital cost savings:
- (a) Intercell bus bar costs are reduced since all buses are below the cell;
  - (b) anode seal costs are eliminated since there are no anode seals;
  - (c) mercury requirements are decreased using the sectioned bottom because higher anode current density is feasible;
  - (d) cell bottom costs are less, particularly for very large 10 cells; and
  - (e) the cell is lighter and supporting structures are less expensive.

(4) Anode stub losses are radically reduced because 15 of the novel means of anode support.

(5) Electrical resistance is decreased because the current to the cell bottom and to the anodes is more uniformly distributed. The novel design provides great flexibility in the electrical contact from titanium to graphite 20 in terms of area and contact pressure not afforded by many prior art designs.

EXAMPLE

A cell constructed essentially as shown in the accompanying drawings has a bottom consisting of five bare segments alternating with four rubber insulated lengthwise segments. The bare segments are channels with a web 12" wide and 50 feet in length. The insulated segments are 5" wide and 45 feet in length. A first group of five graphite anodes, each 14" wide, 6" thick and 48" long are arranged across the cell with each anode centered above a bare segment. The anodes are spaced apart by 3" wide titanium spacer blocks, two per pair of anodes, one near each end of each anode space. Welded to the top of the titanium spacer blocks are vented, inverted titanium caps 2½" across the lower perimeter and 8" high. Threaded into the interior of the bottom of each cup is a 1" copper rod extending downwardly through a polyvinyl chloride sleeve threaded through the cell bottom with ½" clearance between sleeve and rod. The copper rods are threaded into nuts welded to an anode support frame below the cell bottom. The frame is a rectangle of channels adjustably suspended at its four corners from the cell bottom. The frame extends the full width of the cell and along 46" of length. Each additional set of 5 anodes has its own anode support frame and each set is independently adjustable. Ten sets of 5 anodes each fill about 40' of cell. The lower end of the cell is fitted with weirs, float and liquid flow connections as shown in FIG. 5. The upper end of the cell is 7" above the lower end and has inlet lines supplying brine and mercury. Current is applied to the bare segments of cell bottom as cathodes and to the anode support frame which is electrically connected to the anodes. Chlorine and amalgam are produced and removed from the lines provided for this purpose at the lower end of the cell.

What is claimed is:

1. In a flowing mercury cathode cell for the electrolysis of aqueous solutions, said cell comprising an inclined trough having a cell bottom, sides and a cover, inlet and outlet means for said aqueous solution, inlet means for mercury and outlet means for amalgam, chlorine outlet means, anodes supported within said trough and spaced above a mercury cathode flowing over said cell bottom and means for imposing an electric current on said anodes and cathodes, the improved cell bottom and support means comprising in combination:

- (1) An anode support frame adjustably suspended in spaced relation below said cell bottom and insulated therefrom;
- (2) Inverted cups supporting from their lower perimeters a plurality of said anodes in spaced relation to each other and to said cathode;
- (3) Electrically conductive anode support rods extending

- ing upwardly from said frame through apertures in said cell bottom and terminating below the cover of said trough in the bottom of said inverted cups;
- (4) Insulating sleeves spaced from and surrounding said anode support rods from said cell bottom upwardly to the lower perimeter of said cup; said sleeves closing said apertures in said bottom to the flow of said solution, said mercury and said amalgam;
  - (5) Bare lengthwise cell bottom segments alternating with insulated lengthwise cell bottom segments; said apertures in said cell bottom being located in spaced relationship in said insulated lengthwise cell bottom segments and said anode support rods supporting said anodes in juxtaposition to said bare lengthwise cell bottom segments.

2. The combination as claimed in claim 1 in which said cell bottom segments are formed of channels with flanges down and cathode bus means are clamped between and in electrical contact with said flanges.

3. The combination as claimed in claim 1 in which said adjustably suspended anode support frame is provided with threaded suspension rods rotatably attached to said cell bottom and extending downwardly through nuts fixedly attached by insulating means to said frame; said suspension rods terminating at their lower ends below said frame.

4. The combination as claimed in claim 1 having further combined therewith adjustment means for adjusting said spaced relation between said frame and said cell bottom.

5. The combination as claimed in claim 4 in which said adjustment means consists of horizontally rotatable wheels, one fixedly attached to the lower end of each of said threaded rods with endless, flexible drive means engaging a plurality of said wheels and means for rotating said wheels.

6. The combination as claimed in claim 1 having further combined therewith clamping means attached to the lower perimeters of said cups and adapted to engage said anodes.

7. The combination as claimed in claim 1 in which the last of said anode supporting means toward the lower end of said inclined trough is followed by a first means for separating the flowing mercury cathode from said aqueous solution, a second means for separating the gaseous phase in said cell from said aqueous solution and a third means for maintaining the level of aqueous solution in said cell.

8. The combination as claimed in claim 7 in which said first means is a first weir contacting both sides of said cell and extending downwardly into a well formed in said cell bottom to contain said mercury cathode and terminating upwardly below the normal level of aqueous solution in said cell; said second means is a second weir downstream from said first weir, contacting the cover and both sides of said cell and terminating downwardly below the normal level of aqueous solution in said cell; and said third means is a third weir downstream from said second weir, contacting the cell bottom and both sides of said cell, extending upwardly to a level above the normal level of the top of said anodes in said cell.

9. The combination as claimed in claim 7 having a vent in said cover downstream from said second weir.

10. The combination as claimed in claim 7 in which said chlorine outlet means is fitted with a float buoyed by said aqueous solution and adapted to close said chlorine outlet means when the level of said aqueous solution approaches said chlorine outlet means.

11. The combination as claimed in claim 10 in which an additional baffle stands downstream from said last anode support means and upstream from said chlorine outlet; said additional baffle to provide quiescent flow of aqueous solution around said float.

12. The combination as claimed in claim 1 having a vent in the bottom of each of said inverted cups.

13. The combination as claimed in claim 1 in which said cups are composed of a metal selected from the group consisting of titanium, tantalum and alloys thereof containing up to 15% of an element selected from the group consisting of zirconium, niobium and the platinum metals.
